UNITED STATES PATENT OFFICE.

WARREN W. HELLE, OF HINSDALE, ILLINOIS.

STARTING CONTROL FOR INTERNAL-COMBUSTION ENGINES.

Application filed January 22, 1926. Serial No. 82,903.

My invention relates to starting control systems for internal combustion engines, and has to do more particularly with multiple cylinder engines and of the two cylinder type, an object being to provide an improved starting means for more positively starting the engine.

In internal combustion engines and more particularly in the small two cylinder type 10 such as are used as outboard motors for boats, great difficulty is experienced in starting such engines. At times for no apparent reason the engine may be cranked, or spun with rope, many times without getting the 15 engine to fire and continue to run. One of the features of my invention is the provision of means whereby I have been enabled to start such engines usually with the first spin given to the fly wheel.

Generally stated, I have found that by 20 grounding the firing or ignition circuit leading to one of the spark plugs, that is rendering it inactive, and leaving the other one only in circuit, the engine may be started 25 without any difficulty.

For better understanding of my invention reference is to be had to the accompanying drawing, in which—

Fig. 1 illustrates diagrammatically the 30 method of applying my invention to an ignition circuit of a two cylinder engine;

Fig. 1^a is a modified form;

Fig. 2 is a side elevation of a preferred 35 form of switching device adapted to be incorporated in a circuit for applying my improved starting control;

Fig. 3 is a top plan view of Fig. 2;

Fig. 4 is a top plan view similar to Fig. 3, but with the cap and switch knob removed 40 showing the interior stationary contacts;

Fig. 5 is an inside view of the cap of Figs. 1 and 2 showing the wiper; and

Fig. 6 shows the device applied to one of the spark plugs of a two cylinder engine.

Referring now more in detail to the circuit arrangement of Fig. 1, this is the circuit of a Johnson motor modified with my starting control incorporated therein and with the two spark plugs 8-9 of the two cylinders 45 each one grounded in the usual way by its connection with the cylinder or engine. The

particular motor is of the opposed cylinder type in which two charges are fired simultaneously. A source of current is provided in the form of a magneto including the fly 55 wheel 10 with its permanent magnets cooperating with the core 11 of the induction coil having a primary winding 12 and split secondary 13.

Ordinarily the ignition circuit is branched 60 directly to the two spark plugs as 8 and 9, but in my improved starting control I interpose a control element A preferably in the form of a manually operated switch adapted to render the circuit leading to one 65 of the spark plugs inactive, by connecting the live conductor 17 to ground. Thus the spark at the other plug is intensified and a more positive starting is secured. As soon as the motor is started the switch is operated to 70 remove the ground and again connect the inactive plug in circuit for operation.

Included in the primary magneto circuit is a suitable interrupter 14 operated by the cam 15 driven by the motor, and a condenser 16.

In Figs. 2 to 5 I have shown a preferred 80 form of switch or control device A adapted to be readily applied to various makes of outboard motors now on the market, so that my improved starting control may be used without any change in the permanent wiring or mechanism. This switch consists of a casing including an insulating base member 20 supporting a connecting terminal 18 adapted to be applied to the spark plug as shown in Fig. 6 so as to also support the switch. This terminal 18 is preferably of thin sheet metal as copper and is fastened to the base 20 by a screw 21. A grounding 85 contact 22 is also attached to the base 20 by a screw 23 and extends outwardly and downwardly in the form of a spring arm 22 adapted to press against the end of the cylinder as shown in Fig. 6 so as to ground this contact 22. Although I speak of grounding, by 90 this is meant the common return of the circuit.

A central contact plate 24 is secured to the base by a terminal screw 25 to which the ignition conductor 17 is connected. A wiper 100 19 for interconnecting the central plate 24

and thereby the ignition conductor 17 with either the spark plug terminal 18 or the grounded terminal 22 is carried by an operating knob 26 rotatably supported in the top or cover plate 27 by a shaft 28 so that by rotating the knob 26 the brush 19 may be rotated into its various positions. The cover plate 27 is recessed at 27' so as to take the wiper 19, and is also grooved at 27" to fit over the contact plates 18-22 so that the top and bottom plates may be clamped together by the three screws 29.

Although I have shown a preferred form of switching device, it is to be understood that I contemplate employing switches of various types according to the construction of the motors to which they are applied, but I find the form herein illustrated is adaptable for use on a number of different makes of popular outboard motors now on the market, such as the Johnson and the Evenrude, to both of which I have successfully applied my invention.

In applying such switch to the ignition system of an existing motor it is desirable to remove the ignition conductor 17 from one of the spark plugs and attach the switch directly to the spark plug with the ignition wire 17 fastened to the binding post on the lower end of shaft 25 so that the ignition conductor may be operatively connected with the spark plug or grounded through the contact 22 and spring arm 22.

To start the motor the conductor 16 is grounded and the spark plug 8 rendered inoperative shifting the brush 19 to its left dotted position of Fig. 1, after which the motor is given a spin in the usual manner. It will now readily start and as soon as it is running the disconnected spark plug 8 is again rendered operative by manipulating the switch 26.

In Fig. 1^a, I show a modified form of switch circuit in which the ignition conductor 17 is connected permanently to the plug 8 and both grounded when wiper 19 is switched to the contact 22 so that conductor 17 is grounded to increase the intensity of the sparking circuit and plug 8 rendered inoperative during starting.

Although I have shown a manually operated switch for controlling the starting of the motor, I contemplate employing my invention in other ways, such as an automatic control for example, in which one of the spark plugs is normally inoperative and the ignition conductor 17 grounded, but as soon as the engine is running to speed the plug is automatically rendered operative and remains so until the engine stops.

What I claim as new and desire to secure by United States Letters Patent is:-

1. A method of starting control for simultaneously fired opposed twin cylinder

internal combustion engines with series connected spark plugs one of which is in each cylinder, which consists of temporarily rendering active one spark plug only in starting the engine by grounding the ignition conductor leading to the other plug and then rendering both plugs active after the engine is operatively running.

2. A method of starting control for simultaneously fired opposed twin cylinder internal combustion engines with series connected spark plugs one of which is in each cylinder, which consists of temporarily intensifying the ignition circuit by rendering one of the spark plugs inactive and the other active in starting the engine, and then rendering both plugs active after the engine is operatively running.

3. A starting control device for internal combustion engines including a switching device having one terminal for attachment to the spark plug, a second terminal for electrically engaging the engine body to ground said second terminal, and a contact member for connection with a leading in ignition conductor for operatively connecting said spark plug terminal and conductor or connecting said conductor with said second terminal.

4. A starting control device for internal combustion engines including a switch casing, a terminal carried by the casing for attachment to a spark plug of the engine, a spring contact terminal carried by the casing and shaped for yieldingly engaging the engine frame to ground said latter terminal, a terminal for connection with a leading in ignition conductor, and switching means for selectively operatively connecting said ignition conductor terminal and said two other terminals.

5. A starting control device for internal combustion engines including a switch casing, a terminal carried by the casing for attachment to a spark plug of the engine, said terminal supporting the device by its attachment to the spark plug, a spring contact terminal carried by the casing and shaped for yieldingly engaging the engine frame to ground said latter terminal, a terminal for connection with a leading in ignition conductor, and switching means for connecting said ignition conductor terminal with said grounded terminal.

6. A starting control device for internal combustion engines including a switch mounting, a terminal extending from the mounting for attachment to a spark plug of the engine, a second terminal on said mounting having a yielding extension for engaging the engine frame to ground the said second terminal, a third terminal on said mounting for connection with a leading in ignition conductor, and means for con-

necting said third terminal with either the first or second terminals.

7. In combination with an ignition circuit for simultaneously fired opposed twin cylinder engines having two series connected spark plugs one of which is in each cylinder with interposed ignition current supply, of

switch connections for temporarily rendering one of said plugs inactive and intensifying the current supply to the other plug ¹⁰ for starting.

In witness whereof, I hereunto subscribe my name this 18th day of December, 1925.

WARREN W. HELLE.
